GUNNAR EMANUEL MELLGREN, OF TIDAHOLM, AND JOHN GOTTHARD SJÖSTRÖM, OF JONKOPING, SWEDEN

MACHINE FOR MAKING MATCH INNER BOXES

Application filed July 21, 1928, Serial No. 294,380, and in Sweden August 1, 1927.

The present invention relates to an improvement in such machines for making match inner boxes in which the boxes made partially ready on a rotary winding mandrel 5 are pushed over on to a second mandrel on which the joining of the bottoms to the boxes is effected, and from which the finished boxes are afterwards pushed off. Machines of this type as hitherto used almost exclusively, are 10 provided with an intermittently rotating winding mandrel around which the side veneer strip and the paper, which is to join the sides of the box to the bottom, are wound up, and with a non-rotary, but in a direction 15 upwards and away from the winding mandrel movable, second mandrel, the so-called folding mandrel, to the face of which directed towards the winding mandrel the bottom veneer strip is applied, and on to which the 20 side veneer strip and the paper wound up on the first named mandrel are pushed over, after which the box is finished by the paper being folded against and secured to the bottom strip. The finished boxes are then pushed 25 off from the folding mandrel by said mandrel being moved in the rearward direction—away from the winding mandrel—after which the boxes are thrown pell-mell out from the machine by means of a discharger, and 30 are then, while still in disorder, conveyed to a drying apparatus. This entails the disadvantage that afterwards the inner boxes must be put in order before they can be pushed into the outer boxes, or box cases, which are made 35 in another machine.

The present invention has for its purpose to eliminate this disadvantage, and it consists principally in that the machine is provided with a special removing member—or 40 several such members—which is constructed and arranged relatively to the second or folding mandrel in such manner that, after the finished boxes have been stripped or pushed off from said mandrel, said member conveys 45 the boxes away in such manner that during

such removal the boxes retain a predetermined position. By this means the above-mentioned time-wasting work of arranging the inner boxes in order is done away with.

In the accompanying drawings a few embodiments of the invention are illustrated by way of example. Fig. 1 shows diagrammatically an inner box making machine according to the invention, viewed from the side, and Fig. 2 is a section through the same on the line II—II in Fig. 1. Fig. 3 is a side view of a machine with a slightly modified construction of the removing member, and Figs. 4 and 5 show, from two different sides, a machine having a further modified construction of the removing member.

Referring to the embodiment illustrated in Figs. 1 and 2, 1 denotes the intermittently rotating winding mandrel on which the side veneer strip and the paper are wound up, 65 and 2 denotes the folding mandrel mounted opposite the first-named mandrel, which is non-rotary but is movable in a direction towards and away from the mandrel 1, and to the front face of which directed towards 70 the mandrel 1, the bottom veneer strip is to be applied.

When a box blank has been wound up on the mandrel 1, it is pushed by means of any suitable device, not illustrated in the drawing, on to the mandrel 2, on which the box is finished by the paper being folded against and secured to the bottom strip. The finished box 3, which is indicated in Fig. 1 by dotted and dashed lines, is afterwards pushed off from the mandrel 2 by said mandrel being moved in the rearward direction, that is to the right in Fig. 1. Such movement of the mandrel 2 is produced by a spring 4 which maintains a roller 5 on the mandrel rod 6, 85 which is slidably mounted in the machine frame, bearing against a cam disk 8 of suitable shape mounted on the main shaft 7 of the machine.

In this embodiment the above-mentioned 90

removing member consists of an arm 9 which is rotatable on a stationary pin 10 and is connected with a toothed pinion 11 which meshes with a toothed segment 12 on a lever 14 pivoted on the pin 13. Said lever supports at its lower end a roller 15 which bears against a second cam disk 16 on the main shaft 7. The arm 9 is provided with a shoulder 17 so that its outer end outside said shoulder forms a thin tongue 18 which, upon the above-mentioned movement of the mandrel 2 to the right in Fig. 1, moves into a groove 19 in the upper face of the mandrel 2. When the mandrel 2 carrying the finished box 3 moves to the right in Fig. 1, the box will thus be pushed off from the mandrel owing to the upper side of the box striking against the shoulder 17 and its lower portion striking against a stripping-off member 20 secured to the machine frame. In this manner the motion of the box is stopped, whereas the mandrel 2 continues its movement to the right, until the box is made completely free from the mandrel and is only supported by the tongue 18.

Immediately above said tongue is the bent-down forward end of the feed chute 21 which has a rectangular cross sectional shape so dimensioned that it can receive the boxes 3. The chute 21 is pivoted on a stationary pin 22 in the machine frame and is normally maintained in the approximately horizontal position shown in Fig. 1 by a vertically movable slide 23 which supports a roller 24 which bears against a third cam disk 25 on the main shaft 7. As soon as the finished box 3 has been completely pushed off from the mandrel 2 and only hangs on the tongue 18, the arm 9 with its tongue and the box hanging thereon is turned by the influence of the cam disk 16 in the clockwise direction in Fig. 1, whereby the box 3 is moved into the feed chute 21 the lower side of which is provided with a slot 26 for the arm 9. Obviously, the box will thus occupy a position with its bottom directed upwards in the chute 21. When in this manner the arm 9 has delivered the box in the chute 21, the arm is returned by the influence of its weight, or of a spring not shown in the drawing, to the position shown in Fig. 1. In order that during this movement the tongue 18 shall not strike against the opposite side of the box 3, the chute 21 is turned on the pin 22 by the influence of the cam disk 25 and the slide 23 so far upwards that the arm 9 and the tongue 18 may return without taking along the box just delivered. As soon as the arm 9 has been returned to the position shown in Fig. 1 for receiving a new box, the chute 21 is also swung down to the position shown, so that it is ready to receive the next box when the arm 9 is again turned upwards.

The feed chute 21 through which the boxes 3 are caused to move either by their own

weight or by means of a special feeding device, not shown in the drawing, is so dimensioned that the boxes cannot turn or twist in the same. During the entire movement away from the piston 2, both when the boxes hang on the tongue 18, and when they pass through the chute 21, the boxes thus retain a predetermined position. In this determined position the boxes are delivered by the chute 21 on to a table 27, or the like, from which the boxes may afterwards be easily removed without coming in disorder.

The embodiment illustrated in Fig. 3 differs from that above described mainly in that the removing member is arranged in such manner that it catches under the lower side of the boxes 3 when carrying the same away from the mandrel 2 after the boxes have been pushed off from said mandrel. For this purpose the removing member is made in the shape of an arm 28 bent at right angles at two points to approximate Z-shape, said arm being rotatable on the stationary pin 10, as in Fig. 1, and being actuated by the cam disk 16 on the main shaft 7, and the outermost portion of said arm forming the tongue 29 which is to carry along the boxes upon said arm turning upwards. In this embodiment the mandrel 2 is slightly longer than in Fig. 1, and the groove 19 in the upper face of the mandrel shown in Fig. 1 is here replaced by a slot 30 which extends through the mandrel 2 from its upper side to its lower side and allows the bent arm 28 to pass down through the mandrel to the position shown in Fig. 3 for receiving the box when it is being pushed off from the mandrel.

In this case the arm 28 can therefore also take the place of the stationary stripping-off member 20 in Fig. 1, since when the upper and lower sides of the box strike against the arm 28, and the mandrel 2 continues its movement to the right, the box remains resting on the tongue 29. Afterwards the arm 28 is turned on the pin 10 in the clockwise direction and delivers the box in the feed chute 21, which in this case may be rigidly mounted in the machine frame, since here the tongue 29 catches under the lower sides of the boxes, and therefore, the arm 28 is unprevented from turning back to receive the next box.

Finally, in Figs. 4 and 5 an embodiment is shown in which also the removing member is arranged in such manner that it catches under the lower side of the boxes 3, but it is formed of an arm 31 which is rotatable in a plane which is perpendicular to the direction of movement of the mandrel 2. For this purpose the arm 31, which is rotatable on the stationary pin 32, is actuated by a toothed segment 33 on a lever 35 pivoted on the stationary pin 34 and which supports a roller 36 which is maintained by a spring 37 bearing against a cam disk 38 on the main shaft 7 of the machine. When a finished box has

been pushed off the mandrel 2, the arm 31 is turned by the influence of the cam disk 38 in the counter-clockwise direction in Fig. 4, the box 3 being carried along and introduced in the feed chute 21 which, obviously, may also in this case be rigidly mounted in the machine frame. In this case the boxes will obviously be conveyed through the chute resting on one of their long sides.

10 The embodiments above described and illustrated in the drawings are only to be regarded as examples and may of course be modified in several ways as regards their details. It will easily be understood that the
15 removing member may be varied in many ways as regards its shape and its movement, without departing from the principle of the invention which consists in that the box, after being stripped off the mandrel on which it is finished, is caught and removed while retaining a predetermined position. Thus, it is not necessary, for instance, that the box, when stripped off, be caught and removed by one and the same member, as is the case in the
20 embodiments illustrated in the drawings, since the box may just as well be caught by a stationary member, for instance a suitable table which is provided beneath the folding mandrel, afterwards to be removed upwards or to either side by another movable member. Finally, it is also possible, when the box has been stripped off, to allow the same to fall, actuated by its own weight, and guided in suitable manner, to a position below the
25 mandrel 2, and afterwards by means of a movable member to remove the same while retaining a predetermined position. The device illustrated in Figs. 1 and 2, however, has the advantage over the other modifications illustrated and here referred to, that it does not carry along such boxes which become broken when transferred from the winding mandrel to the folding mandrel, and which therefore do not fasten on to the folding
40 mandrel, since such defective boxes cannot be caught by the tongue 18, and the removing member will therefore in this case act also as a sorting member, which is a considerable advantage in practice.

50 We claim:

1. A machine for making match inner boxes, comprising a rotary winding mandrel on which the boxes are partially formed, a second mandrel on which the boxes are finished, means for transferring the boxes from the first to the second mandrel, and means for conveying the finished boxes from said second mandrel and maintaining the boxes in predetermined arrangement during such conveyance.

2. In a machine for making match inner boxes of the character described, having a rotary winding mandrel on which the boxes are made partially ready and from which said boxes are pushed over on to a second

mandrel on which the joining of the bottoms to the boxes is effected and from which the finished boxes are pushed off, the combination of a removing member constructed and arranged in such manner relatively to said second mandrel that after the finished boxes have been pushed off from said second mandrel said removing member conveys the boxes away from said mandrel in such manner that during such removal the boxes retain a predetermined position, and a feed chute in which the boxes are introduced by the removing member in such predetermined position and through which the boxes are transported from the machine.

80

3. In a machine for making match inner boxes of the character described, having a rotary winding mandrel on which the boxes are made partially ready and from which said boxes are pushed over on to a second mandrel 85
slidable towards and away from said winding mandrel and on which the joining of the bottoms to the boxes is effected and from which the finished boxes are pushed off, said second mandrel having a groove in its upper face, 90
the combination of a removing member constructed and arranged in such manner relatively to said second mandrel that after the finished boxes have been pushed off from said second mandrel said removing member 95
conveys the boxes away from said mandrel in such manner that during such removal the boxes retain a predetermined position, and a feed chute in which the boxes are introduced by the removing member in such predetermined position and through which the boxes are transported from the machine, said removing member consisting of a pivoted arm having a tongue adapted upon sliding movement of said second mandrel to enter said groove in its upper face whereby the boxes are caught on said tongue, after which they are introduced in said feed chute by said arm 100
turning upwards. 105

4. In a machine for making match inner boxes of the character described, having a rotary winding mandrel on which the boxes are made partially ready and from which said boxes are pushed over on to a second mandrel 110
slidable towards and away from said winding mandrel and on which the joining of the bottoms to the boxes is effected and from 115
which the finished boxes are pushed off, said second mandrel having a groove in its upper face, the combination of a removing member 120
constructed and arranged in such manner relatively to said second mandrel that after the finished boxes have been pushed off from 125
said second mandrel said removing member conveys the boxes away from said mandrel in such manner that during such removal the boxes retain a predetermined position, and a feed chute in which the boxes are introduced by the removing member in such predetermined position and through which the 130

boxes are transported from the machine, said removing member consisting of a pivoted arm having a tongue adapted upon sliding movement of said second mandrel to enter said groove in its upper face whereby the boxes are caught on said tongue, after which they are introduced in said feed chute by said arm turning upwards, said feed chute being pivotally mounted in the machine frame in such manner that it can be turned aside when said arm is returned for receiving a new box.
